UNITED STATES PATENT OFFICE.

HENRY H. STRATTON, OF CHATTANOOGA, TENNESSEE.

CURTAIN-SHADE FIXTURE.

No. 831,195.

Specification of Letters Patent.

Patented Sept. 18, 1906.

Application filed November 20, 1905. Serial No. 288,267.

To all whom it may concern:

Be it known that I, HENRY H. STRATTON, a citizen of the United States, residing at Chattanooga, in the county of Hamilton and State of Tennessee, have invented a new and useful Curtain-Shade Fixture, of which the following is a specification.

This invention relates to window-curtain-shade fixtures, and has for its object to provide a simply-constructed device whereby an ordinary window-shade roller and shade are adjustably suspended relative to the window-opening and without material structural change in the roller or curtain.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation, it being understood that various changes in the form, proportion, and minor details of construction may be resorted to without departing from the principle or sacrificing any of the advantages of this invention within the scope of the appended claim.

Figure 1 is an elevation from the inside of a window and its casing, with the improvements applied. Fig. 2 is a perspective view, enlarged, of a shade-roller with its end studs. Fig. 3 is a perspective view, enlarged, of the hanger member for the spring end of the roller. Fig. 4 is a view, enlarged, of the hanger for the rotative end of the roller. Fig. 5 is a perspective view, enlarged, of the stud for the rotative end of the roller. Fig. 6 is an enlarged sectional detail of the cord-holding device.

The improved device is applicable to any of the ordinary spring-actuated shade-rollers in common use, and for the purpose of illustration a roller of this class is represented at 10 with a cylindrical stud 11 at the rotative end and an angular stud 12 at the spring end and with the shade 13 attached to the roller in the ordinary manner.

In the improved device the cylindrical stud is provided with spaced stop-collars 14 15, and no other change is made in the roller.

At the circular stud end of the roller a hanger member 16 is disposed having a relatively large aperture 17 intermediately there-

of and with a recess 18 extending radially of the aperture, the larger aperture to permit the passage of the stop-collar 15 and the recess to receive the portion of the stud between the collars. By this means the hanger may be readily attached to the stud and support the same rotatively therein.

At the angular stud end of the roller a clip 19 is disposed over the angular stud and 65 closely engages the same to hold it from turning and is provided with a threaded aperture through which the threaded end 20 of a hanger-rod 21 operates and bears upon the stud within the clip and serving as a set-screw to 70 rigidly connect the parts. The hanger-rod 21 has a terminal eye 22, and the hanger member 16 is likewise provided with a terminal eye 23.

The window-casing (represented at 24) is 75 provided with spaced cord-guides 25 26, which are preferably ordinary screw-eyes, and the hanger-rod 21 and hanger member 16 are provided, respectively, with terminal eyes 22 23, and a pull-cord 27 is connected 80 at the ends, respectively, to said eyes and leads through the guide members and depends over the casing at one side. Attached to the bight 28 of the pull-cord is another cord 29, extending to a point convenient to 85 the hand of the operator. Attached to the casing 24 in position to receive the cord 29 is a cord-supporting member consisting of a disk 30, having a threaded stud for screwing into the casing, and with an inclined inner 90 face 31, between which and the adjacent face of the casing the cord 29 is compressed when wound around the supporting member. By this simple arrangement it will be obvious that the curtain-roller and its shade may be 95 adjusted to any desired point and any required width of the shade displayed over the window-opening and any required portion of the window covered.

The device is simple in construction, may 100 be inexpensively manufactured, and applied to any required size of roller.

Having thus described the invention, what is claimed is—

In a curtain-shade fixture, the combination with a shade and shade-roller, the latter having a cylindrical stud at one end provided with spaced stop-collars and an angular stud at the other end, a hanger having an eye at one end and with a transverse aperture intermediate thereof for receiving said stop-collars and provided with a radial recess for

receiving the portion of the stud between the collars, a clip-bearing over said angular stud and provided with a threaded aperture, a hanger-rod having an eye at one end and with the other end threaded and operating in said threaded aperture and clamping the angular stud against the bottom of the clip, and pull-cords connected to said eyes and adapted to vertically adjust said hanger

members and the shade-roller and shade supported thereby.

In testimony that I claim the foregoing as my own I have hereto affixed my signature in the presence of two witnesses.

HENRY H. STRATTON.
